UNITED STATES PATENT OFFICE.

EDWARD CHARLES FREMAUX, OF RAYNE, LOUISIANA.

RECORD-CABINET.

1,350,146.

Specification of Letters Patent. Patented Aug. 17, 1920.

Application filed October 1, 1919. Serial No. 327,691.

To all whom it may concern:

Be it known that I, EDWARD CHARLES FREMAUX, a citizen of the United States, and a resident of Rayne, in the parish of Acadia 5 and State of Louisiana, have invented a new and Improved Record-Cabinet, of which the following is a full, clear, and exact description.

The present invention relates to a record 10 cabinet and particularly to that class of such cabinets which are adapted to hold disk talking machine records, one compartment being provided in the cabinet for each record whereby the records may be maintained in dust 15 proof holders and selectively removed from the cabinet, means being provided to prevent the record being replaced in its wrong holder.

The primary object of the invention is to provide a simple and practical cabinet for 20 disk records which will insure the records being kept in their proper holders, to which end I propose to provide a plurality of compartments, each of which having an individual locking device whereby the records 25 may be selectively removed, and means for automatically and collectively locking the remainder of the compartments upon unlocking one of the compartments. In this way when a record is removed it will be impossible to replace it in the wrong compartment 30 as the other compartments are locked and inaccessible until the removed record has been replaced.

Further objects will be referred to with 35 reference to the accompanying drawing, the points of novelty being particularly set forth in the subjoined claims. In said drawings,

Figure 1 is a longitudinal section of the cabinet;

Fig. 2 is an end elevation;

Fig. 3 is a longitudinal section showing the parts in different positions from that shown in Fig. 1;

Fig. 4 is a top plan view;

Fig. 5 is a sectional view on the line 5—5,

Fig. 1;

Fig. 6 is a sectional view on the line 6—6,

Fig. 3; and

Fig. 7 is a sectional view of the individual locking device.

Referring to the drawings by characters of reference, a cabinet 1 having a cover 1^a is constructed with a plurality of record compartments, each of which being made up of

a channeled frame comprising grooved side 55 guides 2 with the pivoted grooved arm 3 providing the bottom support for the record. The arm 3 is pivoted as at 4 and actuated by the spring 5 to project the record beyond the top of the compartment. A cover 6 is provided for the compartment consisting also of a grooved member pivoted as at 7 and adapted to swing upwardly and when closed adapted to coöperate with the record 8 in compressing the spring 5 and maintaining 60 the record within the compartment under compression.

Each of the compartments is constructed as just described. Disposed transversely of and along the top of the cabinet is a series 70 of individual locking devices for each of the covers 6, adapted to maintain the covers normally closed but operable to selectively release any one of the covers and permit the spring actuated arm 3 to project the record 75 above the edge of the compartment where it may be conveniently grasped and removed. Each of the locking devices specifically comprises a pivoted spring actuated and vertically disposed rocking lever 9 having a 80 catch 10 adapted to engage the ledges 6' on the lower side of the free end of the cover 6 and maintain the same closed (see, for instance Fig. 1), the spring 11 adapted to normally maintain the lever 9 and catch 10 in 85 locking engagement with the cover 6. Overlying the locking device is a perforated 90 plate 12, the perforations 12 of which being disposed immediately over the groove in the tops of the channel locking levers 9 whereby the finger 13 of a key 14, which is slidably mounted on the rod 15, may selectively engage any of the perforations for rocking the lever 9 and releasing the catch 10 from locking engagement with the cover 6. 95 In other words, the key 14 provides a medium for selectively releasing any of the covers whereby the pivoted arm 3 may be released to project the record in position to be grasped and removed from its compartment.

It very often happens, particularly in those record cabinets where a person must exercise care in replacing the record in its proper place, that a number of records will be removed from the cabinet at one time 100 and replaced regardless of their proper positions. Now according to the present invention this will be impossible in that when the

key 14 has been slid on the rod 15 and actuated to unlock one of the covers I have provided means for automatically and collectively maintaining the remainder of the compartments locked. This is accomplished by means of an apron 16 pivoted as at 17 in the lower corner of the cabinet below the individual locking means above referred to. This apron extends the entire width of the cabinet (see, for instance, Fig. 5) and when inactive it assumes a position as shown in Fig. 1, overlying the elongated ends 3^a of the arms 3. When one of the covers 6 has been unlocked and the record 8 removed, the spring-actuated arm 3 will be swung on its pivot 4 into a position substantially as shown in Fig. 3, with the end 3^a maintaining the apron 16 in abutting relation with the lower ends of the levers 9, which will 20 prevent any rocking motion of the levers, and consequently the key 14 will be unable to rock the levers and disengage the catches 10 from the covers 6. So long as the arm 3 is in raised position not only will the remainder of the compartments be locked as 25 just described, but the compartment from which the record has been removed will also be locked open; in other words, the cover 6 cannot be locked again until the record has 30 been replaced on the arm 3 to press it to normal position. Therefore, when a record is removed it must be replaced in its particular compartment before any other record can be removed or before its compartment can 35 be again locked.

It will often happen that each and every compartment of the cabinet will not contain a record, therefore, some means must be provided for rendering these empty compartments inactive in order that the other compartments may operate properly. To this end a separate and independent locking means, consisting preferably of the screw 18, is adapted to project through the base 40 of the cabinet in position where it may be turned up to engage the end 3^a of the arm 3 and maintain the same inactive (see, for instance, Fig. 1). Each of the arms 3 is provided with this screw locking means, best 45 shown in Fig. 2. Thus any one of the compartments may be selectively maintained inactive by turning up the screw 18 which engages the end 3^a of the arm 3 located in the empty compartment. In some instances, it 50 will be desirable to number the perforations in the plate 12 to correspond to an index number and to likewise number the screws 18 to correspond to the index numbers of the compartments. For instance, if the index 55 gave number "9" as the number of the compartment containing the record sought the key would be moved to the perforation numbered "9" and in this manner open No. 9 compartment. On the other hand, should

the index give No. 9 as empty, the screw 65 numbered "9" will be turned up to maintain this compartment inactive.

The cabinet may be constructed of any dimensions, and any number of compartments may be provided in a single cabinet. 70

If the number index is not employed, each of the covers 6 may be provided with a label identifying the record contained therein.

Having thus described my invention, I 75 claim as new and desire to secure by Letters Patent:—

1. In a dispensing cabinet, a plurality of article holding compartments, a cover for each compartment, a lock for each cover, an 80 article support in each compartment adapted to project the article beyond the compartment upon the unlocking of the cover thereof, and means coacting with the article support for collectively locking the 85 covers of the remainder of the compartments upon the unlocking of the cover of one compartment.

2. In a dispensing cabinet, a plurality of article holding compartments, a cover for 90 each compartment, a lock for each cover, an article presenting support in each compartment adapted to project the article beyond the compartment upon the unlocking of the cover thereof, means for collectively locking 95 the remainder of the compartments upon the unlocking of one compartment, and means co-operating with the article support for maintaining any of said compartments inactive. 100

3. In a dispensing cabinet as set forth in claim 2 and in which the article presenting support for each compartment comprises a pivoted spring actuated arm and in which the said cover co-operates with the article 105 and compresses the spring for holding the article in its compartment under tension of said spring.

4. In a device of the character described, a plurality of article holding compartments, a spring actuated article support in each compartment, an individual locking device for each compartment, and means actuated upon the unlocking of a compartment for automatically locking the remainder of the 115 compartments, said means comprising a pivoted apron adapted to coact with the spring actuated article support and the individual locking device for each compartment. 110

5. In a cabinet of the character described, 120 a plurality of compartments, each made of a channeled frame and adapted to receive a disk record, each of said compartments embodying in its construction a spring actuated pivoted arm adapted to support the 125 record, side members and a cover, the said cover being pivoted and adapted to close its respective compartment, an individual lock

for each cover, a key common to all the locks for selectively unlocking a compartment, said key being slidably mounted adjacent the locks, and an automatic locking device controlled by the unlocking of one compartment for collectively locking the remainder of the compartments.

6. In a dispensing cabinet, a casing having a plurality of article holding compartments, a cover for each compartment, a pivoted and spring pressed locking member for each cover, a pivoted and spring pressed article support in each compartment, and adapted to project the article beyond the compartment upon unlocking the cover, and means operated by the article support and coöperating with the several locking members to hold them in active positions.

7. In a dispensing cabinet, a casing having a plurality of article holding compartments, a cover for each compartment, a pivoted and spring pressed locking member for each cover, a pivoted and spring pressed article support in each compartment and adapted to project the article beyond the compartment upon unlocking the cover, and a pivoted apron operated by the article

support for swinging it into engagement with the several locking members to hold them in active position.

30

8. In a dispensing cabinet, a casing having a plurality of article holding compartments, a pivoted cover for each compartment, a locking member for each cover, pivoted intermediate of its ends, a spring for holding the member in active position, a pivoted and spring pressed article support in each compartment and adapted to project the article beyond the compartment upon unlocking the cover, and an apron pivoted adjacent the lower ends of the locking members and normally overlying the free ends of the several article supports.

9. In a dispensing cabinet, a casing having a plurality of compartments, a cover for each compartment, a pivoted and spring pressed locking member for each cover, each member having a recess in its upper end, an apertured plate above the upper ends of the said members, and a slidable finger above the perforated plate and adapted to be projected through an aperture on the plate into the recess of a locking member.

EDWARD CHARLES FREMAUX.
